UNITED STATES PATENT OFFICE.

NELS PETER PETERSON, OF JEWELL, IOWA.

WHIFFLETREE.

No. 845,663.

Specification of Letters Patent.

Patented Feb. 26, 1907.

Application filed August 16, 1906. Serial No. 330,866.

To all whom it may concern:

Be it known that I, NELS PETER PETERSON, a citizen of the United States, residing at Jewell, in the county of Hamilton and 5 State of Iowa, have invented certain new and useful Improvements in Whiffletrees; and I do declare the following to be a full, clear, and exact description of the invention, such as will enable others skilled in the art to 10 which it appertains to make and use the same.

This invention relates to improvements in whiffletrees.

The object of the invention is to provide a 15 metallic whiffletree which will be simple, strong, durable, and light in construction, means being provided whereby the whiffletree is pivotally connected to the tongue of a vehicle.

20 The foregoing and other objects are accomplished by means of the construction illustrated in the accompanying drawings, in which—

Figure 1 is a plan view of a portion of a vehicle-tongue, showing the application of the 25 invention thereto. Fig. 2 is a front elevation of the whiffletree, showing the tongue in cross-section. Fig. 3 is a cross-sectional view of the whiffletree, showing the tongue 30 in side elevation. Fig. 4 is a detail view of one of the singletrees, and Fig. 5 is a plan view of the lower whiffletree-attaching plate.

Referring more particularly to the drawings, 1 denotes the whiffletree, which consists 35 of an evener-bar 2, formed of upper and lower parallel metal plates or bars 3. Said bars are of suitable width and length and have their ends preferably rounded, as shown. Midway between the ends of the bar 2 the plates 40 3 are provided with alined apertures, through which is adapted to be inserted a pivot-bolt 4. On the bolt 4, between the plates 3, is arranged a coil-spring 5, between the ends of which and the inner sides of the plates 3 are 45 arranged washers 6, through which the bolt 4 also projects. Connected to the plates 3, adjacent to their rear edges and near their ends, are loops 7, with which are adapted to be connected stay chains or straps. (Not 50 shown.)

The outer ends of the plates 3 are preferably bent inwardly, and between said inwardly-bent ends are pivotally-mounted singletrees 8, each of which consists of upper and lower plates 9, said plates being preferably wider at their central portion and

taper gradually toward their ends, as shown. The singletrees 8 are pivotally mounted between the ends of the plates 3 of the evener-bar by means of bolts 10, on which, between 60 the outer sides of the plates 9 and the inner sides of the plates 3, are disposed washers 12. Between the plates 9, forming the singletrees, is arranged a cylindrical spacing-block 13, through which the bolts 10 also pass. 65 The tapered ends of the plates 9 of the singletrees are brought together at their outer ends and have riveted or otherwise secured thereto trace-engaging hooks 14, said hooks being provided with oppositely-projecting ends or points to hold the traces in place and with attaching-plates 15, which are adapted to be engaged with the opposite sides of the ends of the singletrees and to be riveted thereto, as hereinbefore described. 70

On the upper side of the tongue of the vehicle is secured a lower whiffletree-attaching plate 16, said plate consisting of a centrally-disposed circular portion 17, upon which the lower plate of the evener-bar is adapted to 80 rest, and with longitudinal oppositely-projecting attaching portions 18, through which are inserted fastening-screws, by means of which the plate is attached to the tongue. Above the plate 16 is arranged an upper 85 whiffletree-attaching plate 19, said plate having a circular whiffletree-engaging portion 20, on which is formed a longitudinal oppositely-disposed downwardly-curved attaching portion 21, which is secured to the attaching 90 portion 17 of the plate 16 by screws or bolts to fasten the same to the tongue. The whiffletree-engaging portion of the plates 16 and 19 are provided with alining apertures, through which the bolt 4 of the whiffletree is inserted, 95 said bolt also passing through the tongue. On the lower end of the bolt is arranged a nut 22, which is preferably held in place by means of a cotter-pin 23 or other suitable fastening device. 100

A whiffletree constructed as herein shown and described may be used in connection with any vehicle and will be found to be of greater strength and durability and superior in all respects to the common form of 105 wooden whiffletrees.

From the foregoing description, taken in connection with the accompanying drawings, the construction and operation of the invention will be readily understood without requiring a more extended explanation. 110

Various changes in the form, proportion,

and the minor details of construction may be resorted to without departing from the principle or sacrificing any of the advantages of this invention as defined by the appended claims.

Having thus described my invention, what I claim as new, and desire to secure by Letters Patent, is—

1. In an evener, two centrally-perforated plates secured parallel to each other at a distance apart, a singletree pivotally secured at each end of the evener between said plates, said singletree comprising two plates, the central portions of which are at a distance apart and perforated and the ends are tapered and in contact, a hook on each end of each singletree, said hook being provided with oppositely-projecting ends for holding the trace and with attaching-plates which engage with the opposite sides of the singletree and are riveted thereto, and means for securing the evener in position.
2. In an evener, two centrally-perforated

plates secured parallel to each other at a distance apart, a singletree pivotally secured 25 between the plates at each end of the evener, two securing-plates arranged respectively above and below the evener and at right angles thereto, said securing-plates being perforated at their ends to register with each 30 other and at their middles to register with the perforations in the evener-plates, the upper securing-plate being bent upwardly at its middle, a bolt through the central perforations of all of said plates, fasteners 35 through the end perforations of the securing-plates, a spring upon said bolt between the evener-plates, and a washer at each end of said spring.

In testimony whereof I have hereunto set 40 my hand in presence of two subscribing witnesses.

NELS PETER PETERSON.
